(57) **CLAIM**

The ornamental design for a diaper fastener, as shown and described.

DESCRIPTION

FIG. 1 is a perspective view of a first embodiment of a diaper fastener, showing our new design;
 FIG. 2 is a front view thereof;
 FIG. 3 is a rear view thereof;
 FIG. 4 is a left view thereof;
 FIG. 5 is a right view thereof;
 FIG. 6 is a bottom view thereof;
 FIG. 7 is a top view thereof;
 FIG. 8 is a perspective view of a second embodiment of the diaper fastener, showing our new design;
 FIG. 9 is a front view thereof;
 FIG. 10 is a rear view thereof;
 FIG. 11 is left view thereof;
 FIG. 12 is a right view thereof;
 FIG. 13 is a bottom view thereof;
 FIG. 14 is a top view thereof;
 FIG. 15 is a perspective view of a third embodiment of the diaper fastener, showing our new design;
 FIG. 16 is a front view thereof;
 FIG. 17 is a rear view thereof;
 FIG. 18 is a left view thereof;
 FIG. 19 is a right view thereof;
 FIG. 20 is a bottom view thereof; and,
 FIG. 21 is a top view thereof.
 The broken line showing is for illustrative purposes only and forms no part of the claimed design.

1 Claim, 3 Drawing Sheets
